UNITED STATES PATENT OFFICE.

GEORGE E. MARLATT, OF PASADENA, CALIFORNIA.

TYPOGRAPHICAL MACHINE.

Application filed September 29, 1925. Serial No. 59,299.

My invention relates to typographical machines, such as linotype machines of the general organization represented in Letters Patent No. 436,532, to O. Mergenthaler, where-
 5 in circulating matrices are released by es-
 capements from a magazine in the order in
 which their characters are to appear in print,
 and then assembled in line, the composed
 line transferred to the face of a mold, the
 10 mold filled with molten metal to form a
 slug or linotype against the matrices which
 produce the type characters thereon, and the
 matrices thereafter elevated and returned
 through distributing mechanism to the mag-
 15 azine from which they started. More par-
 ticularly, it relates to machines equipped
 with a plurality of magazines containing
 matrices of different font or face, any se-
 lected one of which fonts may be brought
 20 into action at will.

In one class of such machines, (as for instance the U. S. patents, C. Muehleisen, 786,140, March 28, 1905, and H. A. Agricola, Jr., 789,646, of May 9, 1905), the magazines
 25 are arranged in constant relation to the as-
 sembler entrance, having receiving throats
 leading thereto, and the matrix releasing es-
 capements are actuated by reeds which ex-
 tend through the throats or across the lower
 30 ends of the magazines in a single longitudi-
 nal row, thus requiring the matrices to pass
 between closely adjoining reeds in their
 travel from the magazines to the assembler
 entrance. This arrangement of the actuating
 35 reeds necessarily restricts the size or
 thickness of the matrices which can be used
 in the machine, as the space between the
 adjoining reeds is limited and cannot be in-
 creased without objectionably widening the
 40 keyboard and magazines.

Attempts to overcome the above mentioned
 difficulty have been more or less unsuccessful
 chiefly in that they involve objectionable
 45 forms and complications of matrix es-
 capements, and also the holding of the ter-
 minal matrix back a distance from the dis-
 charge end of the magazine and in changing
 the angle or measurement of the discharge
 50 throat immediately adjoining the magazine
 from that which practice has shown to be

most desirable. Practice has shown that
 the best results are obtained if the matrices
 rest flush with the discharge end of the
 magazine and the usual angle of the dis-
 charge throat developed in connection with
 55 the single-magazine type of linotype is ap-
 proximately maintained.

My present invention involves passing the
 escapement operating reeds through the re-
 ceiving throats in several longitudinal rows
 in order that the reeds of each row may be
 widely separated and in addition will oc-
 60 cupy space not traversed by the matrices in
 machines conforming to established measure-
 ments adjacent to the discharge ends of the
 magazines. Further objects of my invention
 are: To simplify and improve upon the key-
 65 board and escapement mechanisms commonly
 employed; to double the number of fonts of
 matrices which may be stored in and released
 from a magazine; to render a change from
 one to another font of matrices a simple and
 70 convenient operation. Minor and contribut-
 ing objects will be disclosed as the descrip-
 tion progresses.

In the accompanying drawings, I have
 shown my invention in preferred form and
 by way of example and as applied to a ma-
 chine of the class stated, but not necessarily
 in preferred form in all circumstances, for
 75 obviously changes and variations may be
 made therein and in its mode of application
 which will still be comprised within its
 spirit, and it may be applied to other forms
 of typographical machines, such as typeset-
 80 ters, typecasters, and the like, which handle
 type or dies other than linotype matrices.
 Generally speaking, I desire it to be under-
 stood that I do not limit myself to any speci-
 85 fic form or embodiment, except in so far as
 such limitations are specified in the claims.

Referring to the drawings:

Figure 1 is an abbreviated side elevation,
 partly in section, of the front or keyboard
 portion of a typographical machine as it ap-
 95 pears embodying my invention, with the key-
 board mechanism in operative relation to the
 lower magazine.

Figure 2 shows the keyboard mechanism in
 operative relation to the upper magazine. 100

Figure 3 shows a modification of means for selecting between the upper and lower magazines.

Figure 4 shows a structural detail.

5 Figure 5 shows modified matrix escapement means and structural details.

Figure 6 is a plan view of the keyboard and the upper magazine shown in Fig. 1, including certain connections therebetween.

10 Figure 7 shows the front end of a magazine with two fonts of matrices arranged in alternate channels thereof. This magazine may be considered either the lower or upper magazine shown in Fig. 1.

15 Figure 8 is a rear elevation of the parts shown in Fig. 1, but not including the upper magazine or the escapement reeds associated therewith.

20 Figure 9 shows means in a non-power-driven keyboard for automatically alternating between two magazine channels each of which contains the same matrix-character.

25 Referring to Fig. 1, the lower magazine 1 rests on a portion 10 of the stationary machine frame to which is secured a crosswise member 11 to receive the forward thrust of the magazine. This member 11 is provided with an undercut groove 12 to receive a tongue 13 forming a part of a bar 14 secured longitudinally to the under side of the magazine. This construction renders it necessary to move the magazine rearwardly a distance sufficient to clear the escapement operating elements 15 before the magazine may be lifted from the machine. The foregoing description applies also to the upper magazine 2 except that the crossbar 11^a is secured to the top of the lower magazine instead of to the machine frame as in the case of the similar member 11.

40 The escapements 3 for controlling the release of the matrices 4 from their magazine channels are similar to and may be precisely the same in action as those described in my copending application Serial No. 546,383. They are pivoted on a rod 5 secured by means of blocks 6 to the top of the magazines. Beneath their pivotal point they enter grooves 7 cut in the top plate of the magazine and serving to space the escapements a proper distance apart while permitting close spacing between adjoining escapements where necessary. The escapement pawls 8 operate through slots 9 in the magazine top-plate. Locating the escapements on top of instead of beneath the magazines leaves the lower matrix channels continuous so that the matrices pass readily through and from their channels.

45 60 It will be noted that the escapement-operating reeds 15 are positioned close to the delivery throat wall 17 in order that the branch throats 28 and 30 may be the correct length to properly conduct the 65 matrices to the main throat 18 occupied by

the delivery belt 53. As thus positioned the reeds 15 displace certain structures and mechanism commonly attached to the wall 17, or to which said wall is attached, but the manner of sub-grouping the reeds 15 leaves sufficient space between the groups of reeds to attach the usual structure to the wall 17, the method of attaching the bracket 22 of this invention being an example.

70 The escapement operating reeds 15 are, for the most part, arranged in transverse groups of three, for each magazine, therefore in a machine having ninety keys there would be thirty transverse rows of three reeds each for each magazine. But the 75 number of reeds in the transverse rows may vary from the numbers given when the magazines are supplied with two fonts of matrices as hereinafter explained and as 80 illustrated by the drawings. In the drawings the groups of three reeds are shown in connection with the small letter side of the magazine where space is limited, while in connection with the capital letter side the 85 reeds are variously positioned so that their upper ends 15^a need not be offset an extreme 90 distance to meet and engage associated escapements. In the case of fonts of small 95 matrices, the magazines are intended to contain two fonts in alternating channels. 100 Otherwise stated, if the channels were numbered consecutively, the even-numbered 105 channels would contain one font of matrices and the odd-numbered channels would contain a second font. For example, a magazine 110 wide enough to accommodate a single 115 font of 20-point matrices would be wide enough to contain one font of 8-point and one font of 10-point matrices, and since one font would be idle while the other was 120 in use, the reeds 15 are made to occupy positions in front of the idle font and are shiftable from one position to another according to the font selected for use. When positioned in front of an idle font their escapement-operating ends 15^a are in engagement 125 with the escapements controlling the release of matrices from the active font. In addition, the reeds 15 occupy the same planes as the usual partitions 16, which are shiftable 130 therewith; therefore, neither the reeds nor the partitions occupy any space which would be of use in conducting the matrices from the magazines, provided the magazines contain two fonts of matrices. In Fig. 7 two 135 fonts of matrices are shown in their channels, and in Fig. 6 the reeds 15 are shown in full lines in engagement with the escapements controlling the release of the right hand or thinner font, and in broken lines 140 at the right of Fig. 6 the reeds 15 and partitions 16 and 26 are shown shifted to the left with the reeds in engagement with the 145 escapements controlling the left hand or thicker matrix font. The reeds and parti- 150

tions are rendered thus shiftable as follows: The stationary back wall 17 of the throat 18 is provided with a groove 19 in which rests the lower edge 20 of the plate forming the floor 21 of a branch 28 of the throat 18. At its upper end the plate 21 rests on the stationary bracket 22 and is loosely keyed thereto by means of a flat rod 23. The plate 18 is thus capable of endwise movement in the groove 19, and the extent of its movement is limited by means of a pin 24 and slot 25 (Fig. 8) connection, the slot being in the plate 18 and the pin being a continuation of a screw 24 serving to secure the bracket 22 to the throat wall 17. Several partitions 26, lying in the planes of the partitions 27 which space apart the upper and lower channel plates of the magazines, serve to interconnect the floor 21 of the lower channel branch 28 and the floor 29 of the upper channel branch 30. Similarly, the channel partitions 16 enter openings 31 and 32 in the upper and lower channel floors respectively and are therefore movable with said floors. The front wall 33 of the throat 18 is hingedly connected by means of a rod 34 to the partitions 16 for movement therewith, and the escapement-operating reeds 15 pass through suitable openings 35 and 36 in the floors of the branch throats and are movable therewith for placing their upper ends in engagement with a selected set of escapements 3. Thus the parts forming the matrix delivery throat as a whole may be moved a slight distance in either direction according to the font of matrices selected for use and may be readily grasped from the front or keyboard side of the machine and shifted as desired.

The angular endings 15^a of the operating reeds are guided in slots 37^a formed in a channeled member 37 supported on and shiftable with the delivery throat partitions 16 and 26, the lower channeled member 45 receiving support only from the several partitions 26. The lower wall of the channeled member 37 limits the downward or return movement of the reeds 15 and retains them in position for engagement with the escapements when a magazine is placed or replaced in the machine, the reeds fitting loosely in a notch 3^a in the escapements, and the weight of the reeds holding the escapements securely when in normal position.

The reed endings may be flattened as at 15^b (Fig. 8) in order to properly engage the escapements. Since the reeds 15 are shiftable a fixed distance and the escapements are variously spaced apart according to the spacing of the matrix channels, the forward ends of the escapements are variously bent as shown in order that each pair comprised of an idle and active escapement may be equally spaced at their reed-engaging ends 65 regardless of the unequal spacing of the

matrix channels beneath the escapements. When the magazines are designed to contain only a single font of thick matrices the channels may be spaced apart accordingly and the escapements on any particular magazine 70 may be bent according to the spacing of the channels therebeneath relative to the ends 15^a of the reeds.

In Fig. 5 is shown a modification in which the ends 15^c of the reeds are bent in line with the path of their movement and form the escapement, the direct connection between the keyboard and the escapement point timing the action of the reed 15 with the movement of the matrices so that only one 80 matrix at a time will escape unless more are desired. A normal touch of a keyboard key will release one matrix, and two or more matrices may be released with a single touch according to the length of time a key is held 85 depressed. In quadding out a line, for example, the key may be held depressed until the line is full. The ends 15^c of the reeds enter between the fore and aft lugs of the matrices successively following the release of 90 each terminal matrix from its channel. This form of escapement is well adapted for use where only a single font of matrices are contained in a magazine and the magazine is not frequently removed from the machine. 95 When this form of escapement is employed and a magazine is to be lifted from the machine one of several well-known locking means may be used to prevent spillage of the matrices from the magazine.

In Fig. 5 is also shown an optional method of guiding the reeds 15 through the channel floors 21 and 29. In this showing the reeds comprising each group pass through a continuous slot 21^a or 29^a and are separated one 105 from another by rods 26^a supported in the partitions 26. The same slots which guide the reeds 15 may also receive the edge of the partitions 16.

Two optional methods of selecting between the upper and lower magazines are illustrated in the drawings. The keyboard 38 is preferable similar to that described in my co-pending application Serial No. 546-383, the key levers 39 terminating in the 110 same horizontal plane. In the present showing they are guided and spaced apart near their terminations in slots 40^a formed in an opened square tube 40 anchored by means of pins 41 to the keyboard end plates 38^a. The opening 40^b in the member 40 permits the upwardly projecting ends of the key levers to engage and actuate the reeds 15 and a rod 42 limits the return movement of the key levers. The parts are so proportioned 115 that when the rod 42 is withdrawn, the key levers may be removed from or inserted in their guiding slots 40^a. Most of the reeds 15 are offset in two directions near their lower ends, one offset bend placing the series 120

of reeds for each magazine in a longitudinal row at their lower ends and another bend spacing them uniformly apart according to the spacing apart of the key levers 39. The 5 reeds 15 are guided in a shift plate 43 supported on rods 44 extending through the keyboard and is covered by the keyboard tray 45. Individual reeds of a series occupy slots 43^a in the shift plate and the two series 10 of reeds are separated by a rod 43^b, a similar rod 43^c retaining the outer series in position. This arrangement permits the reeds to be readily removed and replaced for repair or other purposes. The forward edge of the 15 shift plate terminates in a handle 43^d and this handle contacts with the keyboard tray to limit the rearward movement of the shift plate, the forward movement thereof being limited by pins 43^e. When the shift plate 20 is forward the rear series of reeds (those associated with the lower magazine) are in position to be actuated by the key levers 39, as shown in Fig. 1, and when the shift plate is moved to the rear as shown in Fig. 2 the 25 front series of reeds (those associated with the upper magazine) are in position to be actuated.

The optional method of selecting between the two magazines is shown in Fig. 3 and 30 consists in guiding the reeds 15 in a fixed plate 46 secured to the throat wall 17, and rendering the keyboard as a whole shiftable in its frame 47 in order to place the rear terminations of the key levers in operative relation to a selected series of reeds 15. A pin 48 and slot 49 connection determines the extent of movement of the keyboard in its frame.

Individual members of each sub-group of 40 each series of reeds 15 have a slight pivotal movement in the openings 35 and 36 when the plate 43 is shifted, and a continuous opening 21^a in the floor 21 of the lower branch throat permits the necessary movement of the reeds associated with the upper magazine when a shift is made. These openings 21^a are of sufficient length to receive 45 projections 16^a of the partitions 16 and 26 as best shown in Fig. 8, and a rod 50 extends through the projections 16^a and serves to retain the partitions in place. The openings 21^a are of sufficient width and the partitions of such length and flexibility that the endwise movement of the channel floor 21 50 is not hindered when selecting between two fonts of matrices in a magazine in the manner described. The partitions 16 and 26 may be anchored at their lower ends or elsewhere by means of split plugs 51 in 55 the wall 17, a pin 52 passing through the halves of the plug and a projection 16^b of the partitions. This anchoring arrangement does not differ materially from that commonly employed, but in the present case the 60 plugs 51 may be so positioned relative to the

length of the partitions that their lower ends may be caused to approach the matrix delivery belt 53 when a shift is made for a font of thin matrices and move away from the belt when a shift is made for a font of thick matrices, thus regulating the distance between the belt 53 and the ends of the partitions according to the thickness of the matrices which must pass therebetween. To this end fonts of thick matrices should be 70 arranged in right-hand (even numbered) channels and thin matrices in left-hand (odd numbered) channels of the magazines, which is the reverse of the order shown in Fig. 7.

It is common practice in machines of the linotype class to provide two magazine channels for matrices carrying the letter "e", in order that a shortage of this letter will not occur when assembling long lines of 80 small matrices, a device known as the "double e attachment" being provided for automatically shifting from one to another channel of "e" matrices at the completion of each line in the assembler (not shown). The device referred to is designed for use with a 85 power-driven keyboard, hence is not applicable to the keyboard herein illustrated. I therefore provide a special device for this purpose, as illustrated in Figs. 8 and 9. The rear termination of the "e" key lever 39^e is 90 forked and embraces a ratchet 54 pivoted for rotation between the fork branches 39^b. The teeth of the ratchet element are central on the face thereof and at each side of the teeth are four engaging surfaces *a* and four clearances *b*, which surfaces and clearances are staggered relative to their occurrence on opposite sides of the ratchet teeth, a clearance *b* on one side of the teeth being opposite an engaging surface *a* on the opposite side 95 thereof.

The escapement-operating reed designated 100 15^e controls the release of matrices from the first "e" channel in the magazines and the reed designated 15' controls their release 110 from the second "e" channel. As the key lever 39^e is depressed at its forward end the ratchet 54 rises with the rear end thereof and one of the "e" reeds will be cleared through one of the clearances *b* while the other "e" reed will be engaged by one of the 115 engaging surfaces *a*, according to the position of these staggered portions as controlled by an operating pawl 55. Thus each time the ratchet is turned one tooth a shift is 120 made from one to the other of the "e" reeds. This shift occurs incident to the raising of the assembler to deliver the matrix line to casting position, the assembler being raised by means of a handle 56 on a shaft 57 which 125 is connected in usual manner to the assembler. To operate the double "e" device I secure to the shaft 57 an arm 58 which through a link 59, a swinging arm 60 hung from one of the keyboard fulcrum rods 61 130

for supporting the link 59, and the weighted escapement-operating pawl 55 communicates tooth-by-tooth movement to the ratchet 54 each time the assembler operating handle 56 is returned after being depressed and presents alternately a clearance *b* or an engaging surface *a* to each of the "e" releasing reeds, operativeness being shifted from one to the other of the reeds as each succeeding line of matrices is assembled, the matrices being withdrawn from one magazine channel while they are being distributed to the other. The spacing between the two series of reeds 15 may bear such relation to the size of the ratchet 54 that the "e" reeds of one series will clear the ratchet while those of the other series are under control thereof. The construction of this multiple letter device is such as to permit of its use at any point across the width of the keyboard, so that it may be applied for use in connection with characters other than the "e", or in connection with spaces and leaders.

From the foregoing description it will be apparent that I have provided a typographical assembling mechanism of simple construction in which the elements are visible and accessible and which permits a shift from one to another of four fonts of matrices to be readily accomplished from an operator's position at the keyboard. Assuming the matrices to be of the 3-character kind provided for in my Patent No. 1,310,487, such a machine equipped with two magazines will supply twelve faces or styles of type and by lengthening the branch delivery throats to accommodate a third series of reeds a third magazine may be added, providing a capacity for eighteen type faces in a 3-magazine machine; or, when three magazines are employed the same series of reeds which actuate the escapements on top of the middle magazine may be employed to actuate escapements on the bottom of the top magazine, or the escapements on top of the middle magazine may actuate those on the bottom of the top magazine provided the matrices are locked against spillage and free of their escapements on the idle magazine. Where a third branch throat is added I prefer the forwardly curved form thereof illustrated as the upper delivery throat in my Patents Nos. 1,266,970 and 1,366,578; also, where the escapements of a middle magazine are made to operate those beneath a top magazine, I prefer the form of escapement illustrated in said patents for the reason that their forward ends operate in the same direction as the forward ends of the escapements of this invention and which may be lengthened forwardly to actuate the escapements beneath an upper magazine. In like manner the rear series of reeds of this invention as illustrated with two magazines could be made to operate the escapements of

the upper magazine, but the shift from one to another magazine would not then be so convenient as that herein described. It may be noted also that the means herein described for shifting from one to another font of matrices in a single magazine would also serve for shifting from one to another magazine each containing a single font of matrices. In such case a single series of reeds could be employed if each reed were provided with upper and lower escapement-operating angles 15°; or, the two series of reeds could be employed and made to terminate in a single row or otherwise at their lower ends and either the reeds or the keyboard key-levers rendered relatively shiftable lengthwise of the keyboard in order to place alternate reeds in operative relation to the key levers. Also, the magazines could be rendered shiftable edgewise relative to the escapement-operating reeds of this invention for selecting between fonts of matrices whether contained in one or more magazines. For fonts of thick matrices the alternations of the channels could occur with one set of channels in one magazine and the other set thereof in staggered relation thereto in the other magazine, or the channels could be one above the other and the escapement ends or operating reeds differently offset accordingly so that only one set of escapements at a time would be operative. It will be understood that the broader claims hereto appended are intended to embrace any such obvious modifications as those above suggested.

Having thus described my invention and its mode of operation, what I claim as new and desire to secure by Letters Patent of the United States, is:

1. In a typographical machine having magazines containing fonts of matrices arranged in channels irregularly spaced apart according to the thickness of the matrices in individual channels, two fonts of matrices arranged in alternating channels of said magazines, two corresponding sets of escapements irregularly spaced apart according to the spacing of said channels, actuating devices for said escapements, and means for selectively connecting said actuating devices with one or the other of said sets of escapements regardless of the irregular spacing apart thereof, said means consisting in bending portions of said escapements so that all pairs of alternating escapements will be equally spaced at the point where they are engaged by the said escapement-actuating devices.
2. In a typographical machine having a magazine containing two fonts of matrices arranged in alternating channels therein for selective use according to font, two correspondingly alternating sets of escapements above said magazine for controlling the release of individual matrices therefrom, a

single set of devices for actuating said two sets of escapements, a channel through which said matrices travel when released from said magazine and through which said escapement-actuating devices extend to engagement with the escapements above said magazine, and means for moving said escapement actuating devices in either direction relative to alternating channels in said magazine so that they may be positioned in a non-interfering relation in front of an idle font of matrices when an active font of matrices is associated with said escapement actuating devices for release from their magazine.

3. In a typographical machine having a magazine containing two fonts of matrices arranged in alternating channels therein for selective use according to font and having means for releasing individual matrices of a selected font from their channels, a channeled throat for conducting the matrices from their channels, partitions separating the channels of said throat, and means for moving said partitions in either direction relative to alternating channels in said magazine in order that they may occupy non-interfering positions in front of idle magazine channels while relatively alternating channels are active.

4. A combination as specified in claim 3 characterized by the fact that the means therein recited for releasing the matrices from their magazine channels are reeds occupying positions in the planes of the said channel partitions and are movable therewith to non-interfering positions relative to the path of said matrices through said throat.

5. In a typographical machine having a magazine containing fonts of matrices arranged in alternating channels therein for selective use according to font, escapements above said magazine for releasing matrices therefrom, a channeled and partitioned throat through which said matrices travel when released from their channels, a series of escapement-operating reeds extending through said throat to engagement with said escapements above said magazine and arranged in sub-groups of said series in the planes of the partitions separating the channels of said throat, and means for moving said throat, said reeds and said partitions as a unit in either direction relative to pairs of said alternating magazine channels in order that said reeds and said partitions will occupy positions in front of idle magazine channels and will not interfere with the travel of the matrices through said throat when released from active channels of said magazine.

6. A combination and structure as specified in claim 5, including also a second magazine above said recited magazine, a

second series of sub-grouped reeds for operating the escapements thereof, and a second channeled and partitioned throat for conducting matrices therefrom, the sub-groups of reeds associated with said second magazine occupying positions in the planes of said partitions in common with said first recited sub-groups of reeds and being movable therewith selectively to non-interfering positions relative to the path of travel of the matrices through said second throat.

7. In a typographical machine, in combination, a magazine having a series of closely-spaced-apart channels for conducting matrices therethrough and permitting of their individual release therefrom, correspondingly spaced-apart fulcrumed escapements for controlling the release of matrices from said channels, and non-interfering means for retaining said escapements in their spaced-apart positions, said means being a series of grooves formed in a channel plate of said magazine adjacent the fulcrum points of said escapements and each entered by a portion of a related escapement to prevent its displacement from operative relation to a related magazine channel.

8. In a typographical machine, in combination, superposed magazines containing matrices capable of individual release therefrom, a separate series of reeds associated with each of said magazines for controlling the release of matrices therefrom, a keyboard having key levers for actuating said reeds, a structure permitting but one at a time of said separate series of reeds to occupy direct operative position relative to said key levers, and means for shifting one or another of said series of reeds to direct operative relation to said key levers when an associated magazine is selected for use.

9. A combination as specified in claim 8, including also a keyboard tray and characterized by the fact that the means therein recited for shifting said series of reeds to operative position selectively is a plate underlying said tray and serving as a guide for said reeds at the rear of said keyboard and terminating in a handle at the front of said keyboard.

10. In a typographical machine, in combination, a magazine having matrices therein, escapements on top of said magazine for releasing the matrices therefrom, escapement-operating elements overlying the front end of said magazine and separate therefrom, and a structure compelling the rearward movement of said magazine so as to clear said escapement-operating elements preliminary to removing said magazine from its support.

11. In a typographical machine, in combination, magazines containing fonts of thick matrices and fonts of thin matrices, a delivery belt for conveying said matrices to

an assembling station, partitions between which said matrices pass to said delivery belt, means for shifting from one to another of said fonts of matrices, and coacting means for causing the ends of said partitions to approach or retreat from said delivery belt to accommodate the thickness of mat-

rices passing between said belt and the ends of said partitions.

Signed at Pasadena, Los Angeles County, ¹⁰ California, this 22nd day of September, 1925.

GEORGE E. MARLATT.
